UNITED STATES PATENT OFFICE.

ERNST CHRISTENSON, OF STOCKTON, KANSAS.

GATE-OPERATING MECHANISM.

1,391,095.

Specification of Letters Patent. Patented Sept. 20, 1921.

Application filed July 21, 1921. Serial No. 486,375.

To all whom it may concern:

Be it known that I, ERNST CHRISTENSON, a citizen of the United States, residing at Stockton, in the county of Rooks and State 5 of Kansas, have invented certain new and useful Improvements in Gate-Operating Mechanism; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to railway crossing gate operating mechanism, the construction being such that the train will cause the gate or barrier to swing into obstructing position parallel with the track and whereby the train will also cause the gate or barrier to move out of obstructing position or in other words, raise it in a substantially vertical plane.

20 The novel construction of the gate operating mechanism will be apparent by reference to the following description in connection with the accompanying drawings, in which—

25 Figure 1 is a perspective view of a gate operating mechanism constructed in accordance with my invention.

30 Fig. 2 is a top plan view of the weight guide and shiftable weight forming part of the invention.

35 Fig. 3 is a side view of the same showing the normal position of the parts, the weight being at one end of the guide in position to be tripped.

40 Fig. 4 is a similar view showing the weight at the limit of its downward movement at one end of the guide, and

45 Fig. 5 is a view showing the weight shifted to the opposite end of the guide ready to tilt it.

Referring now to Fig. 1:

1 and 2 designate the rails of a railway track, to one side of which is a casing 3 inclosing certain gate operating mechanism 5 to operate the gate or barrier 4, which may be provided with a hinged section 5 adapted to swing out when the barrier 4 is in a horizontal plane and to fold, as shown in Fig. 1, when the barrier is in a vertical plane. 55 The gate or barrier 4 is fixed to a rock shaft 6 journaled in a bearing 7 at one end of

the casing 3 and journaled in a bracket bearing 8 secured to one side of the casing 3, as will be clearly apparent by reference to Fig. 1. 60

The rock shaft 6 carries at one end a notched segment 9, adapted to be engaged by a detent 10 supported by the horizontal shaft 11, pivoted in a bearing 12 carried by the casing 3. The detent 10 is in the form 65 of an elbow lever and the projecting portion 13 is engaged by one end of a spring 14, the other end being fastened at 15 to the casing 3 so that the detent 10 will normally engage the slot or notch 16 in the segment 9. 70

The shaft 11 extends through the casing, being journaled in the bearing 17 in one end of the casing 3 and on its free end is an arm or lever 18, having oppositely disposed extensions 19 and 20. The upper extension 19 has connected to it a flexible connection 21, adapted to pass through the guide 22 supported from the post 23, which may be a telegraph pole or other convenient support. One end of the flexible connection 80 21 is fastened to the depending arm 24 of a rock shaft 25, journaled in bearings 26 and 27, supported by the ties or similar support 28 between the rails 1 and 2. The rock shaft 25 is provided with an upstanding throw lever 85 or arm 29, as will be clearly apparent by reference to Fig. 1.

At a convenient point adjacent to the track is a support 30, which may be a telegraph pole, carrying a spring or yielding 90 arm 31, connected to the arm 24 by the connection 32 so that the arm 31 will normally tend to maintain the arm 24 in position as shown in Fig. 1 and thereby maintain the throw lever 29 in a vertical position. The 95 spring 14 preponderates over the spring arm 31 so as to normally maintain the dog or detent 10 in the notch 16.

The arm 20 is connected to a connection 100 similar to 21, 24, etc., in an opposite direction to the throw lever 29 so that the device can be operated if a train is moving in either direction. The shaft 6 is provided with a pinion 33, which is in mesh with the teeth 34 of a rack bar 35, slideable in guides 36 105 and 37, the guides 37 being shown in Figs. 3, 4, and 5. The rack bar 35 is also provided with rack teeth 38 at right angles to the teeth 34 and the latter teeth engage a segmental rack 39 rigid on the trough-shaped weight guide 40, which is pivoted on bearings 41. The segmental rack 39 is pro- 110

vided with a rock shaft 42, having a depending arm 43, which engages the piston rod 44 of a check 45 pivoted at 46 to the bracket 47.

5 The rock shaft 6 is also provided with a crank 48, having a link 49 pivoted at 50 to an elbow lever 51 which, in turn, is pivoted at 52 to the casing 3, the lower arm of the elbow lever carrying a weight 53 above 10 the spring bracket 54 supported by one end of the trough-shaped guide 40. The bracket is adapted to contact with a spreading stop 55, as will be explained hereinafter.

The end of the trough guide 40 opposite to 15 the spring bracket is provided with a throw arm 56, pivoted at 57 to the under side of the guide 40 and provided with a stop 58 which is normally held against the guide by a spring 59. The free end of the throw arm 20 normally rests above one arm of a U-shaped swinging lever 61 journaled in a bracket 62 carried by the inner wall of the casing 3, the other arm 63 being adapted to lie on the opposite side of a disk 64 carried by the rock 25 shaft 65 and journaled in the bearing 66 in one end of the casing 3. The rock shaft 65 carries an upstanding arm or throw lever 67, as will be clearly seen in Fig. 1 and this lever is adapted to reset the mechanism to normal 30 position so that the gate or barrier will be raised as shown in Fig. 1. The disk 64 carries on one face two pins 68 and 69 which are adapted to engage the under side of arm 63 so that when a train strikes the lever 67 35 and rocks the disk 64, either of the pins will strike arm 63 and cause arm 60 to raise the throw arm 56 and push a ball or weight 70 to the opposite end of the trough guide 40, where it will pass under and be held by the 40 spring bracket 54 to exert a downward pressure on the opposite end of the guide.

The disk 64 is provided on its opposite face with two cam projections 71 and 72 which lie in the path of the ball 70 when 45 the parts are in normal position so that when the disk is turned by a passing train, the cam projections will also strike the ball and assist in driving it back to the far end of the guide 40. The operation is as follows:

50 Suppose a train is coming down the track from left to right, it will first strike the arm 29, pulling the arm 24 in a direction away from the casing 3, rocking the shaft 11 to withdraw the detent 10 so that the ball or 55 weight 70 will cause the rack bar 35 to raise and swing the gate in a horizontal plane or substantially so. The gate will remain in this position until the train strikes the arm 67, when one of the cams 71 or 72 and the 60 throw arm 56 will strike against the ball 70, thus throwing the ball to the opposite end of the trough-shaped member, where it will remain poised behind the depending lip 73 of the spring bracket 54 and overweight that 65 end of the trough-shaped member 40 to such

an extent as to cause the gate to be raised by actuating the rack bar 35 and the gate will be held in the raised position by the detent 10, which will be snapped into the notch 16 through the medium of the spring 14. The 70 operation of raising or lowering the gate will be gradual due to the check 45.

When the end of the trough-shaped member carrying the bracket 54 has been lowered to its limit (this being slowly accomplished 75 on account of the check), the lip 73 will contact with 55 and allow the bracket to free enough to permit the ball 70 to escape so that it may run to the position shown in Figs. 1 and 3, but the gate cannot drop to horizontal 80 position until the train has struck the arm 67.

It is to be noted that the ball gets its first impetus by one of the cams 71 or 72 striking thereagainst and as the arm 67 continues to swing, one of the pins 68 or 69 will strike the arm 63, raising the arm 60 so that a second blow will be imparted to the throw arm 56 to give additional force to the ball and to insure that the ball rides into the space confined by the bracket 54.

90 The gate or barrier 4 may be provided with a counterbalance so as to reduce the required power necessary to operate it. Therefore, comparatively little power will be required to raise it from a horizontal to a vertical position.

Attention is also called to the fact that when the ball is trapped by the bracket 54 and starts to rock, the end of the trough-shaped member 40 which carries the bracket 54, will not be below the opposite end of the trough-shaped member before the ball is released. Therefore, the ball will always move back to the position shown in Fig. 1 when the lip has contacted with the stop 54 so as 105 to spread the bracket to allow the escape of the ball.

What I claim and desire to secure by Letters-Patent is:

1. A gate operating mechanism comprising a barrier having a vertical swinging movement, a rock shaft to which the barrier is rigidly secured, a crank on said shaft, a counter-balance weight connected to the crank, a pinion on the shaft, a rack meshing with the pinion, a rocking trough-shaped weight guide, a toothed member on the guide meshing with the rack to operate the rack when the guide rocks, a rolling weight in the guide, a detent for normally holding the rock shaft inoperative, and train-actuated means for withdrawing the detent.

2. A gate operating mechanism comprising a barrier having a vertical swinging movement, a rock shaft to which the barrier is rigidly secured, a crank on said shaft, a counter-balance weight connected to the crank, a pinion on the shaft, a rack meshing with the pinion, a rocking trough,

shaped weight guide, a toothed member on the guide meshing with the rack to operate the rack when the guide rocks, a rolling weight in the guide, a detent for normally holding the rock shaft inoperative, train-actuated means for withdrawing the detent, and additional train-actuated means for tilting the trough-shaped guide.

3. A gate operating mechanism comprising a barrier having a vertical swinging movement, a rock shaft to which the barrier is rigidly secured, a crank on said shaft, a counterbalance weight connected to the crank, a pinion on the shaft, a rack meshing with the pinion, a rocking trough-shaped weight guide, a toothed member on the guide meshing with the rack to operate the rack when the guide rocks, a rolling weight in the guide, a detent for normally holding the rock shaft inoperative, train-actuated means for withdrawing the detent, and additional train-actuated means for tilting the trough-shaped guide, the second mentioned train-actuated means comprising a rock shaft, a disk on the rock shaft and means on the disk for striking the rolling weight to tilt the guide.

4. A gate operating mechanism comprising a barrier having a vertical swinging movement, a rock shaft to which the barrier is rigidly secured, a crank on said shaft, a counter-balance weight connected to the crank, a pinion on the shaft a rack meshing with the pinion, a rocking trough-shaped weight guide, a toothed member on the guide meshing with the rack to operate the rack when the guide rocks, a rolling weight in the guide, a detent for normally holding the rock shaft inoperative, train-actuated means for tilting the trough-shaped guide,

the second mentioned train-actuated means comprising a rock shaft, a disk on the rock shaft and weight striking cams on the disk.

5. A gate operating mechanism comprising a barrier having a vertical swinging movement, a rock shaft to which the barrier is rigidly secured, a crank on said shaft, a counter-balance weight connected to the crank, a pinion on the shaft, a rack meshing with the pinion, a rocking trough-shaped weight guide, a toothed member on the guide meshing with the rack to operate the rack when the guide rocks, a rolling weight in the guide, a detent for normally holding the rock shaft inoperative, train-actuated means for withdrawing the detent, additional train-actuated means for tilting the trough-shaped guide, the second mentioned train-actuated means comprising a rock shaft, a disk on the rock shaft and weight striking cams on the disk, a swinging lever for simultaneously striking the weight, and means on the disk for actuating the lever.

6. A gate operating mechanism comprising a rock shaft, a gate rigid with the rock shaft, means for normally holding the rock shaft inoperative, train-actuated means for releasing the rock shaft, a rocking guide member tiltable about a horizontal axis, means connecting the rocking guide member and the shaft to operate the shaft, a weight longitudinally movable in the guide to tilt the guide member, a check connected to the guide, means at one end of the guide for normally retaining the weight against movement and a releasing stop member for releasing and permitting the weight to automatically return to normal position.

In testimony whereof I affix my signature.
ERNST CHRISTENSON.
